VOLTAGE REGULATOR

John L. Schermerhorn, East Orange, N. J., assignor to American Transformer Company, Newark, N. J.

Application October 6, 1936, Serial No. 104,176

9 Claims. (Cl. 171—119)

This invention relates to a voltage regulator which includes a transformer having a core and winding thereon preferably arranged in the form of an auto-transformer. In many respects my present regulator has many characteristics in common with the voltage regulators shown and described in Hunter patents 1,993,007, issued March 5, 1935; and 2,014,570, issued September 17, 1935. However, the regulator to be herein-after described is designed more particularly for smaller currents or watt capacity.

It is the principal object of my present invention to provide a relatively low-wattage voltage regulator which will give exceedingly close voltage regulation at high efficiency; and a regulator that is cheap to manufacture, yet one that is strong and durable.

Other advantages will be discerned by one skilled in this art, from a reading of the specification, taken in connection with the annexed drawings, wherein:

Figure 1 is a part-elevational and part-sectional view through the regulator, certain parts being removed or omitted from the view to better illustrate the other parts.

Figure 2 is a top plan view of Figure 1, but on a reduced scale, with all the parts positioned, except the cover which is shown in dotted line.

Figure 3 is a bottom view of Figure 1, with all the parts positioned, except the cover which, as in Figure 2, is shown in dotted line.

Figure 4 is a view on the line 4—4 of Figure 1.

Figure 5 is a view on the line 5—5 of Figure 1.

Figure 6 is a view of the brush holder such as shown in Figure 1 but of a slightly modified method of making connection to the brush holder per se.

Figure 7 is a detailed perspective view to illustrate the contact of the brush with the winding.

Figure 8 is a side elevation of a modified form of brush holder.

Figure 9 is a view of Figure 8 looking at the spring side of the holder.

Figure 10 is a view of the brush holder per se, looking from right to left of Figure 8.

Figure 11 is an end view of the bottom part of Figure 8.

Figure 12 is an elevational view of a polyphase regulator; that is to say, one using a plurality of units shown in Figure 1.

Referring now to the details, wherein like numbers refer to corresponding parts in the various views, 1 is the core of a ring type transformer. As shown, the core 1 is preferably made up of a single strip of silicon steel ribbon

spirally wound into ring form, although it will be understood that the core 1 may be constructed in other ways; for example, it may be made out of discs or washers punched from suitable sheet stock, but a core of this construction is very wasteful in material. The spirally wound ring core has another very special advantage over a stack of discs in that, with the discs, it is necessary to provide an insulating tube fitting tightly over the outer surfaces of the discs as a back support for that part of the winding which acts as a brush track or commutator. Where the core is made out of a single piece of steel ribbon, spirally wound, it provides a very solid back support so that the special insulating cylinder is not required, but the core may be exteriorly wound with sheet insulation which is wrapped tightly around it and treated with a suitable insulating varnish or equivalent. This is less expensive than the special tube and makes a more satisfactory construction. This insulation around the core is indicated by the numeral 2.

Wound over the insulation 2 is a winding 3 which is of a suitable size wire chosen according to the watt capacity of the regulator. The winding 3 is preferably cotton- or fabric-covered, enamel wire, which I have found far preferable to plain enamel wire, because the turns are better insulated, and the fabric covering will absorb the insulating varnish or equivalent, making the whole winding moisture-proof and more durable than the winding of plain enamel wire.

After the core 1 has been wound with the winding 3, I apply, to the exterior circumferential surface thereof, a pair of spaced bands 4 and 5 which are preferably made of treated insulating material, to prevent expansion and which serve a plurality of purposes, in one of which the bands, which are preferably made up of a plurality of turns of treated fabric, prevent expansion of the winding, thereby serving to hold the brush or commutator section 6 securely in place between the bands, under normal operation of the movement of the brush over the track, it being understood that the insulation is removed from the winding between the bands 4 and 5 to leave a bare track surface or commutator section 6. The bands also act to prevent movement of the wires or conductors at the track or commutator section when pressure is applied to the transformer structure by the holding-down clamps. The bands 4 and 5 also act to prevent the brush holder, to be later referred to, from coming into engagement with the the bare con-

ductors forming the track 6, when the brush is worn down or, for any reason, becomes broken.

The core 1 and winding 3 of the transformer structure are held between two spider type clamps 5 and 8. The spider 8 is composed of three spaced arms extending from a central hub 9 which is closely fitted to a tubular member 10 having a flange 11. The arms 8 of the spider have, at their extremities, curvilinearly shaped seats 10 which are adapted to engage insulators 12 that rest on the edge of the transformer. In a similar manner, the bottom spider 7 has three spaced arms extending outwardly, each having a curvilinearly shaped seat to engage insulators 13 around the bottom edge of the transformer.

The spider 7 has a hub 14 which is adapted to fit over the end of the tubular member 10 which is threaded at 15 to receive a clamping nut 16 which, when set up, securely clamps the transformer between the two spiders 7 and 8. The arms of the spider 7 have extensions or feet 17 having holes 18 therein for mounting the regulator on a suitable support. Also, these extensions are provided with shoulders 19 for receiving and supporting an outer case 20, which has been indicated in dotted lines and which serves to completely enclose the regulator when necessary. Also, the arms of the spider 7 have flanges 19 positioned to receive devices used in connection with the regulator. For example, by reference to Figure 3, one pair of the flanges 19 have attached thereto, by screws 20, a terminal strip 21 of insulating material carrying contact studs 22, 23 and 24. It may be noted that to the terminals 22 and 24, are connected the ends of the winding 3. Another pair of flanges 19 carries a name plate 25, on which the usual data or indicia is affixed. It is to be noted that the arms of the spider 7 have ribs 26 to further strengthen the said arms. The use of this style of clamps has several advantages over solid plates, in that free circulation of air is provided through the inside of the regulator for cooling purposes. In addition, the construction described reduces the weight and assists in accurately lining up the core with the shaft mounting, to be later described.

Located in the bottom end of the tubular member 10, is a shouldered bushing 27 which is centrally bored to receive one end of an operating shaft 28, the bushing being fastened to the shaft 28 by a set screw 29. Mounted in the top part of the cylindrical member 10 is another shouldered bushing 30, through which the shaft 28 passes and is fastened to the bushing 30 by a set screw 31. The top part of the shaft 28 carries an operating hand-wheel 34. The bushing 30 has an arm 32 which may be integral therewith, or which may be fastened thereto. The arm 32 extends radially outwardly over the top of the transformer and, at its extremity, there is fastened a depending member 33, at the lower end of which is fastened, in any satisfactory manner, as by screws and nuts, generally referred to as 34, a pair of spaced members 35 having the two parts extending at right angles to each other, and between which is pivotally mounted, on a stud 36, a brush holder 37.

The brush holder 37, as shown in Figures 1, 4 and 5, is composed of two pieces of suitable metal fastened together by bolts or studs 38 and 39, between which is clamped a brush 40. As will be seen, by reference to Figure 1, the two parts of the brush holder 37 are long enough to extend over the bands 4 and 5 so that, after the brush 40 becomes worn sufficiently, or for any reason

becomes broken, the brush holder 37 will contact with the bands 4 and 5, which are of insulating material and cannot contact with the track or commutator surface 6, which would injure the track surface and also short-circuit several turns 5 of the winding. Since the brush holder 37 is pivoted at 36, the brush and holder may oscillate in a vertical plane, so that the brush 40 will be self-aligning along the track surface between the bands 4 and 5. In other words, the brush 40 will 10 be held substantially parallel with each and every turn of the winding and, due to the flanged construction of the parts 35, the holder 37 will have no movement which will take the brush out of its position just described. 15

As shown in Figure 1, the brush is connected through a flexible conductor 41 with a stud 42 to which is connected a cable 43 which passes to the interior of the tubular member 10, and one or more times around the shaft 28, and through an opening 44 in the tubular member 10, to the terminal stud 23 (see Figure 3). It is to be understood that the stud 42 is insulated from the member 33.

The necessary pressure of the brush on the 25 commutator or track 6 is obtained by reason of a spring member 45. The conductor cable 43 is held in position in the arm 32 by a suitable clip 46. In the form shown in Figure 6, the cable 43 is carried to the brush holder 37 in a little 30 different manner than shown in Figure 1, in that it passes through a hole 47 in the arm 32 and directly to the intermediate connecting stud 42, thereby eliminating the hole 48 in the member 45 (see Figure 5). 35

In Figures 8 to 11 inclusive, the brush holder and connections are somewhat different than heretofore described. In these figures, the cable 43 passes through the arm 32 as in Figure 6, but runs directly to the brush holder and is fastened 40 thereto by one of the studs or bolts 38. As will be seen, by reference to Figures 8 and 11, the back side of the brush holder has a semi-circular seat formed therein for the round head 49 of a stud or pin 50, which is slidably held by the 45 member 33 and the outer end of which is engaged by a spring 51, similar to the spring 45, but a little differently shaped. This construction allows the brush 40 to oscillate about the head 49 of the pin 50 without twisting or weaving, 50 for the same purpose as described with respect to the construction shown in Figure 1, thus allowing the brush to make contact throughout its entire length on a conductor of the brush track or commutator surface 6. It should be noted 55 that the arm 32 is provided with a lug 52 adapted to engage a stop 53 on one of the arms of the spider 8 so as to stop the rotation of the arm 32 after it is turned by the hand-wheel 34.

By reference to Figure 1, it is to be noted that 60 there is a space between the lines 55 which marks the beginning and end of the winding of the transformer, and the stops 52 and 53 are arranged on the arm 32 and clamp 8 so as to stop the brush 40 on opposite sides of the said space, according 65 to how the arm 32 is turned.

By reference to Figure 7, it will be noted that the contact end of the brush 40 is beveled so that the contact face of the brush is substantially the width of one of the conductors, just the same as 70 in the heretofore referred to Hunter patents, wherein the brush is preferably not thicker than the thickness of one of the commutator bars illustrated. Furthermore, the brush 40 is constructed of precisely the same material as the 75

brush described in said Hunter patents; that is to say, the material is of such a nature as to have sufficient resistance in association with the turn of the transformer that no detrimental short-circuit occurs when the brush passes from one conductor to the next, it being understood that in this condition the brush spans two adjacent conductors, so that the circuit in which the voltage is being regulated is never opened, and little or no fluctuation of current occurs therein. It may be mentioned that the width of the track is made compatible with the length of the brush so the face area will be sufficient to carry the current without overheating and sparking.

15 The construction of the regulator is such that a plurality of them may be mounted in tandem by bolts passing through the holes 18 in the extensions or feet 17, at the same time providing a longer shaft to go through the units, the arm 20 for each regulator being connected to the shaft by means of the necessary bearing bushings fitting in the tubular member 10, of a length to correspond to the number of units to be connected in tandem for multiple or polyphase 25 operation of a plurality of the regulators. Such a regulator for a three-phase circuit is shown in Figure 12, wherein the studs 57 are supplied with spacing collars 60 and nuts 58 for holding two of the unit regulators in spaced relation. The studs 30 57 terminate at some point 63 to receive the threaded ends of collars 61, thereby holding all the units in tandem relationship. The free ends of the collar 61 may be threaded at 62 for mounting the regulator on a panel, in which case, suitable brace members are engaged by the nuts 59 35 on the lower ends of the studs 57. Where this type of regulator is mounted on a stand or base, it may be clamped thereto by the nuts 59, it being understood that the studs 57 pass through the 40 base or support member.

It may be noted, in passing, that if the core is made of a single strip of magnetic material as described, I prefer to anneal it after rolling it up, and before the outer insulation and winding is put on.

Furthermore, it may be mentioned that while Figure 7 shows the brush 40 with a slightly tapered point, this is not necessary, except where the regulator is of very low capacity and the 50 wire of the transformer winding is of relatively small diameter. In the larger capacities of this type of regulator, where the turns of the winding 3 are of such size as to give the brush the necessary mechanical strength at its face, the brush is 55 not beveled.

From what has been said, it will be seen that certain changes may be made in the details entering into the construction of my improved type of regulator. It will also be understood that 60 while I prefer to use a single winding, the winding may be separated into a primary and secondary, the brush running on a similarly constructed track on the secondary winding. If the primary and secondary are used, they may be arranged 65 and connected so that the brush need only travel over a small portion of the outer periphery of the secondary.

What I claim is:

1. A voltage regulator including an annular 70 core, a winding surrounding said core, with means for making electrical connection thereto, said winding being bared on its outer circumferential surface to form a brush track, a tubular member centrally located within and passing through 75 the core, clamping members carried by said tubu-

lar member at opposite ends of said core with means for clamping them against the core and winding, a shaft rotatably located within said tubular member and having an arm extending radially over one end of the winding, means for rotating the shaft, a brush holder carried by said arm, a brush carried by the holder so as to run on said track, means for making a working electrical connection to said holder, and means for preventing the holder from contacting with the track when the brush wears out or becomes broken.

2. A voltage regulator as set forth in claim 1, further characterized in that said last-mentioned means includes insulating bands on opposite sides of the brush track, the brush holder being of a length to overlap the bands, and the bands being of a thickness to prevent the holder from touching the track when the holder engages the bands.

3. A voltage regulator including an annular core, a winding surrounding said core, with means for making electrical connection thereto, said winding being bared on its outer circumferential surface to form a brush track, a tubular member centrally located within and passing through the core, clamping members carried by said tubular member at opposite ends of said core with means for clamping them against the core and winding, a shaft rotatably located within said tubular member and having an arm extending radially over one end of the winding, means for rotating the shaft, a brush holder carried by said arm so as to oscillate in a plane including an element of said track, a brush carried by the holder so as to run on said track, and means positioned over the winding adapted to engage the holder under certain conditions to prevent the holder from engaging the track.

4. A voltage regulator as set forth in claim 1, further characterized in that the bottom end clamping member has flanges thereon for mounting thereon devices such as a terminal-connecting strip carrying terminals for the winding and brush lead, and a number plate, and further characterized in that said bottom clamping member has feet for mounting the regulator, and shoulders for receiving and attaching a cover thereto.

5. A voltage regulator including an annular core, tight-fitting insulation around said core to form a solid support for a commutator or brush track, an insulated winding over said core and having a space going nearly around its outer circumferential surface bared to form a brush track, clamping members carried by said tubular member at opposite ends of the core and having spaced arms for engaging the side of the core and winding bands going around the winding on opposite sides of said track at least to prevent expansion of the winding and movement of the commutator or track conductors when pressure is applied to the core and winding by said clamping members, a tubular member centrally located within and going through the core, means for tightening the clamping members in securing position, a shaft rotatably carried by said tubular member, means on the shaft for rotating it, an arm operated by the shaft, a brush holder carried by said arm so as to be oscillatable in a plane including a conductor of the track, a brush, substantially the width of a conductor of the winding, carried by the holder in engagement with the track, a terminal board on the bottom clamping member, and a conductor supported by said arm for carrying current from the brush and

holder through said tubular member to a terminal located on said board, the bottom clamping member having flanges on its arms for carrying the terminal board, said arms on the bottom 5 clamping member having shoulders to receive a cover, and also having holes therein for mounting the regulator.

6. A voltage regulator including an annular core comprising a strip of magnetic material arranged in concentric turns initially tightly wound and covered with a tightly fitting cover of insulating material, a winding around the core on said insulating cover, said winding being securely anchored to the core by spaced binding 10 means and being bared, on its outer circumferential surface in a belt extending nearly around the core and between said spaced binding means, to form a commutator or brush track, a tubular member centrally located within the core, clamping 15 members carried by the tubular member at opposite ends of the core and having parts for gripping the sides of the core and winding, a shaft rotatably and removably carried within said tubular member, means for rotating the shaft, 20 an arm mounted for rotation with the shaft, a brush rigging including a holder carried by said arm, a brush carried by the holder in contact with the surface of said track, the brush being substantially the width of a conductor forming 25 part of the track, and the holder itself being mounted so as to insure that the brush is self-aligning along the length of a conductor of the track.

7. A voltage regulator as set forth in claim 6 further characterized in that said binding means comprises two rings of material preferably of insulating tape tightly wound over the winding at opposite sides of the track.

5

8. A voltage regulator as set forth in claim 6, further characterized in that said brush is seated in a holder which is carried by said arm, so the brush and holder can swing about a pivot in a plane including a conductor in said track for the 10 purpose described.

9. A polyphase voltage regulator comprising a plurality of units arranged in tandem; each unit including an annular core, a winding surrounding the core with means for making electrical 15 connection thereto, said winding being securely bound to the core and bared on its outer circumferential surface to form a commutator or brush track; a tubular member passing through the core of each of said units, sets of clamping members carried by the tubular member, one set for each unit, at opposite ends of its core, with means for clamping them against their respective cores and windings, a shaft rotatably located within said tubular members and having an arm for 20 each unit extending radially over the end of its winding; means for rotating the shaft; a brush holder carried by each of the unit arms, a brush carried by each of said holders to engage its respective commutator or track, the said clamping 25 members having feet for receiving means to anchor the units together in spaced relation.

JOHN L. SCHERMERHORN.
